COOLING AND DISPENSING DEVICE

Carl L. Daun, Milwaukee, Wis., assignor to Daun & Co., Chicago, Ill., a corporation of Illinois

Application June 2, 1950, Serial No. 165,833

4 Claims. (Cl. 62—141)

1

This invention relates to a cooling and dispensing device for drawing carbonated beverages from a container and while it is primarily intended for effecting the cooling and dispensing of beer from any standard keg or barrel, it may be utilized expeditiously for other beverages in other containers.

The primary object of the present invention resides in the provision of a new and improved refrigerated tap rod, adapted for use in connection with the standard tap bush on a keg or barrel, which is simple in construction and effective in operation for the rapid and efficient cooling of beer during its passage through the tap rod in the course of its being drawn from the barrel and delivered to the dispensing faucet, which in many instances is attached directly to the upper extremity of the tap rod.

Another object of the present invention resides in the provision of a new and improved refrigerated tap rod which includes, in its unitary structure, a capillary tube that serves a plurality of purposes; firstly, as a metering device for controlling the flow of refrigerant into the tap rod to insure the desired flooded condition of the rod with refrigerant and, secondly, as a means by which the refrigerant is delivered to the tap rod in unexpanded condition to insure the optimum advantage of the initial expansion of the refrigerant for effecting the rapid cooling of the beer as it is drawn through the tap rod from the bottom of the barrel and delivered to the dispensing faucet.

Another object of the invention resides in the provision of a new and improved refrigerated tap rod which includes a capillary tube for delivering a refrigerant, in unexpanded condition, to a refrigerant jacket surrounding a centrally disposed beer passage and extending substantially the entire length of the beer passage whereby the refrigerant jacket is effective to materially reduce the temperature of the beer as it is being drawn through the beer passage in the tap rod during the dispensing operation.

Another object of the invention resides in the provision of a new and improved refrigerated tap rod comprising a plurality of concentrically arranged thin-walled metal tubes of high thermal conductivity including a central tube extending the entire length of the tap rod and forming a beer passage therethrough, an intermediate tube cooperating with the central tube to delineate a refrigerant passage surrounding the central passage and extending substantially the entire length of the central tube, and an outer tube

2

cooperating with the intermediate tube to delineate a continuation of the refrigerant passage surrounding the first named refrigerant passage and extending upwardly from the lower end thereof throughout the portion of the tap rod disposed in the barrel, and a capillary tube for delivering a refrigerant, in unexpanded condition, to the refrigerant jacket surrounding the central beer passage in the tap rod.

10 A further object of the invention lies in the provision in a refrigerated tap rod of a new and improved combination of elements assembled into a unitary structure which includes a metering device for controlling the flow of refrigerant into the tap rod to insure maximum efficiency of operation by maintaining the refrigerant passage of the rod constantly filled.

20 A further object of the invention lies in the provision of a refrigerated tap rod adapted for use in a refrigerating system without requiring the inclusion of an expansion valve, an element previously deemed essential in systems of this type.

25 A further object of the invention lies in the provision of a refrigerated tap rod constructed in a manner to permit a plurality of these rods to be connected in parallel relationship in a single refrigerating system without requiring the use of an expansion valve in the system.

30 A further object of the invention lies in the provision of a refrigerated tap rod constructed in a manner to permit a plurality of these rods to be connected in parallel relationship in a single refrigerating system with each rod functioning independently of the other rod or rods in the particular system.

35 A more specific object of the invention lies in the structural arrangement and combination of the several elements of the new and improved refrigerated tap rod.

40 Other objects and advantages will become apparent from the following description of an illustrative embodiment of the present invention shown in the accompanying drawings.

45 In the drawings:

Figure 1 is an elevational view of a beer barrel, partly in section, showing the application of a refrigerated tap rod, constructed in accordance with the teachings of the present invention and illustrating diagrammatically its connection in a refrigerating system;

50 Fig. 2 is an enlarged fragmentary elevational view of the refrigerated tap rod of the present invention showing its application to a standard tap bush of a barrel;

55

Fig. 3 is an enlarged fragmentary vertical sectional view of the refrigerated tap rod showing the details of construction of its several associated parts;

Fig. 4 is a top plan view of the refrigerated tap rod;

Fig. 5 is a horizontal sectional view, taken on the line 5—5 of Fig. 3, showing the passage for admitting the refrigerant to the refrigerant jacket;

Fig. 6 is a horizontal sectional view, taken on the line 6—6 of Fig. 3 showing the positioning of the capillary tube in the upper portion of the tap rod;

Fig. 7 is a horizontal sectional view, taken on the line 7—7 of Fig. 3 showing the inlet and outlet ports through which the refrigerant is admitted to and discharged from the tap rod;

Fig. 8 is a horizontal sectional view, taken on the line 8—8 of Fig. 3 showing the concentric arrangement of the several tubes of the rod which cooperate in a manner to form a central passage for conducting the beverage upwardly through the rod, an intermediate passage, surrounding the central passage, for conducting the incoming refrigerant downwardly through the rod, and an outer passage, surrounding the intermediate passage, for conducting the outgoing refrigerant to the discharge port of the rod; and

Fig. 9 is a bottom plan view of the tap rod showing the passage through which the beverage enters the lower end of rod from the container.

Before entering into a detailed description of the illustrative embodiment of the present invention, it is believed that a brief discussion of the principles of its operation in comparison with other devices for similar purposes will serve to emphasize the more important features of the tap rod of the present invention.

Refrigerated tap rods of the type now in general usage require the inclusion, in the refrigerant circuit, of an expansion valve which operates intermittently in response to variations in conditions in the circuit to replenish the supply of refrigerant in liquid form to replace the amount which has been vaporized in the process of absorbing heat from the beverage being cooled. In circuits of this type, the expansion of the refrigerant begins immediately upon its release from the expansion valve, which is almost universally positioned at or near the compressor for the purpose of convenience and in all instances in a position remote from the tap rod. With this condition present, the initial expansion of the refrigerant serves to no useful end since its heat absorbing properties are wasted in cooling the atmosphere surrounding the refrigerant lead to the rod as evidenced by the presence of frost on these lines at all times. A further disadvantage of a refrigerating system embodying an expansion valve lies in the fact that it is necessary to hook up a plurality of rods, in the event that more than one may be required, in series connection with the result that the effectiveness of each succeeding rod in the series of rods is greatly reduced as the heat absorbing properties of the refrigerant have been materially dissipated in effecting the cooling of the contents of the preceding rods.

The refrigerated rod embodying the teachings of the present invention overcomes the several difficulties mentioned in the next preceding paragraph by providing a refrigerated tap rod of new and improved construction adapted for use

in a refrigerating system without requiring the inclusion of an expansion valve in the system. A further advantage of the new and improved refrigerated tap rod lies in the fact that a metering device, in the form of a capillary tube, forms an integral part of the tap rod to insure the maintaining of the desired flooded condition of the rod with refrigerant at all times since the size of the orifice and the length of the tube are calculated with such nicety as to permit the admission of a sufficient volume of refrigerant to satisfy the heat exchange demands of the rod. Another advantage of the present rod lies in the fact that the inclusion of the capillary tube insures the delivery of the refrigerant in unexpanded condition to the refrigerant jacket of the rod so that its initial and most rapid heat absorbing action takes place at the most advantageous position in the refrigerant circuit; namely, in the tap rod and surrounding the passage through which the beer to be cooled is being drawn. A still further advantage of the present rod lies in the fact that the inclusion of the metering device in each rod permits a plurality of these rods to be hooked up in parallel relationship in a single refrigerant system with positive assurance that each rod will function effectively and independently of the other rod or rods which may be included in the refrigerant circuit of the particular installation.

The refrigerated tap rod, chosen for illustrative purposes in the accompanying drawings, is constructed in accordance with the teachings of the present invention and comprises generally a plurality of fittings and a plurality of tubes adapted to be assembled into a unitary structure embodying the invention. The refrigerated tap rod includes a central or intermediate fitting 10, preferably a machined casting of brass or other rust resistant material, an upper end fitting 11 having the same characteristics, a lower end fitting 12 which may be a screw machine part, and a plurality of concentrically arranged thin-walled metal tubes of high thermal conductivity including a central tube 13, an intermediate tube 14 and an outer tube 15 which surrounds the lower portion of the tubes 13 and 14. A casing tube 16 surrounds the upper portion of the tubes 13 and 14 and forms a protective covering for a capillary tube 17 which connects the fittings 10 and 11 in a manner and for a purpose to be hereinafter more specifically described. The hollow center of the tube 13 forms a beverage passage 18 which extends the full length of the tap rod. A refrigerant passage 19, extending substantially the entire length of the tube 13, is formed between the outer surface of the tube 13 and the inner surface of the tube 14 to provide a refrigerant jacket completely surrounding the beverage passage 18. The lower end of the refrigerant passage 19 opens into a continuation passage 20 extending upwardly from the lower fitting 12 and into the intermediate fitting 10. This refrigerant passage 20 is formed between the outer surface of the tube 14 and the inner surface of the tube 15 to provide a refrigerant jacket surrounding the lower portion of the tube 14 and extending upwardly throughout the length of that portion of the tap rod disposed within the barrel to which the rod is attached; so that the contents of the barrel is effected by the cooling action of the refrigerant as the refrigerant passes through the tap rod.

Referring more specifically to the structural details of the embodiment of the invention shown

in the accompanying drawings, the body portion of the intermediate fitting 10 is substantially cylindrical in shape provided with an axially disposed central bore 21 sized to slidably receive and position the intermediate portion of the tube 14 which is soldered or brazed in proper position to form a fluid tight seal with the bore 21. An enlarged axially disposed bore 22 extends upwardly from the bottom of the fitting 10; the bore 22 being sized to slidably receive the upper portion of the outer tube 15 which is also brazed in fluid tight connection with the bore 22. A turned surface 23 on the upper portion of the fitting 10 serves to slidably receive the lower portion of the casing tube 16 which is also tightly secured in place. The fitting 10 includes an inlet boss 24 projecting laterally therefrom and having an inlet port 25 threaded to receive a standard coupling forming a part of the refrigerant circuit. An axially disposed drilled hole 26 serves as a passage to connect the inlet port 25 with one end of the capillary tube 17 which is secured in fluid tight connection with the upper portion of the hole 26. An outlet boss 27 projects laterally from the side of the fitting 10 opposite the inlet boss 24, and is provided with an outlet port 28 threaded to receive a standard coupling forming a part of the return line of the refrigerant circuit. A passage 29 serves to connect the refrigerant passage 20 with the outlet port 28.

The lower end fitting 12 of the tap rod is provided with an axial bore 30 within which the lower end of the central tube 13 is secured in fluid tight connection. A slot 31 formed in the bottom surface of the fitting 12 serves as a passage through which the beverage enters the lower end of the beverage passage 18. The upper end of the fitting 12 may be provided with threads 32 to afford a suitable means for securing it tightly upon the lower end of the tube 15.

The upper end fitting 11 is provided with an axially disposed central bore 33 adapted to slidably receive the upper end of the central tube 13 which is secured in fluid tight connection in the bore 33. An enlarged axially disposed bore 34 extends upwardly from the bottom of the fitting 11 and serves to slidably receive the upper end of the intermediate tube 14 which is tightly secured in the bore 34. An intermediate bore 35 serves as a passage to connect the refrigerant passage 19 with a cavity 36 formed in the fitting 11. An axially disposed drilled hole 37 extending upwardly from the bottom surface of the fitting 11 serves as a passage to connect the cavity 36 with the upper end of the capillary tube 17 which is secured in fluid tight connection with the lower portion of the hole 37. The upper end 38 of the fitting 11 is fashioned in a manner to receive any standard beer faucet which may be releasably retained thereon in the usual well known manner. The outer diameter of the fitting 11 is sized to be slidably received in the upper end of the casing tube 16 to which it may be secured in any desired way to form a tight reconnection therewith.

A brief description of the functioning of the refrigerated tap rod in connection with a refrigerating system will serve to advantage in presenting the operation of the rod in effecting the rapid and efficient cooling of beer during its passage through the tap rod. In the illustrative refrigerating system, shown diagrammatically in Fig. 1, any conventional vapor compression machine may be employed including a compressor

40, a condenser 41, a refrigerant supply line 42, and a return or suction line 43. The free ends of the supply and return lines for the refrigerant are each provided with standard couplings arranged to be connected respectively with the threaded inlet port 25 and outlet port 28 located in the intermediate fitting 10 of the tap rod. It should be noted, at this point, that the refrigerating system in which tap rods of the present invention are incorporated do not require the use of an expansion valve in the system. The elimination of the expansion valve from the refrigerating system represents a marked departure from and advance in the state of the art pertaining to systems of this type and it is made possible by the inclusion, as an integral part of the tap rod, of a metering device, illustrated in the form of a capillary tube, for controlling the flow of refrigerant into the tap rod.

With the tap rod inserted into the barrel and secured in the tap bush in accordance with standard practice and the couplings of the supply and return lines of the refrigerating system connected respectively to the inlet and outlet ports of the tap rod, the device is installed and ready for operation to effect the cooling of the contents of the barrel as it is drawn through the tap rod during the normal dispensing operation. In the present system, refrigerant flows under pressure from the condenser 41, through the supply line 42 and is delivered in unexpanded condition into the inlet port 25 of the tap rod. The refrigerant, still in unexpanded condition, passes through the passage 26, then through the capillary tube 17, the length and size of orifice of which serves as a metering device for controlling the volume of flow of the unexpanded refrigerant to the refrigerant passage 19 through passage 37, cavity 36 and intermediate bore 35. As the refrigerant enters the cavity 36 from the small orifice of the tube 17, it begins to expand and becomes effective to absorb heat rapidly from the column of beer in the passage 18 of the central tube 13 as the refrigerant flows downwardly through the passage 19 which forms a refrigerant jacket completely surrounding the thin-walled tube 13, formed of material having high thermal conductivity, throughout substantially its entire length. As the refrigerant leaves the open lower end of the passage 19 it enters the refrigerant passage 20 which forms a refrigerant jacket surrounding that portion of the tube 14 which normally is disposed within the beer barrel or beverage container. As the refrigerant passes upwardly through the passage 20 it continues to cool the passage 19 and also absorbs heat from the contents of the barrel in which it is immersed. One of the important advantages of the present tap rod lies in the fact that the refrigerant passages 19 and 20 in the tap rod are maintained in substantially flooded condition to insure highly efficient operating characteristics for the rod. The maintaining of the desired flooded condition of the refrigerant passages is accomplished by establishing a balanced condition between the requirements of the rod and the amount of refrigerant necessary to meet these requirements. This proper balance is established by calculation and experimentation and is maintained in the rod by making the length of the tube 17 and the diameter of its passage to correspond with the particular requirements of the rod.

The improved efficiency of the present refrigerated tap rod is based upon the combination of novel features embodied in the rod. The

most important single feature of the present rod is the provision, in the unitary structure, of a metering device which is effective to accomplish several advantageous results. One major advantage of the built-in metering device resides in the fact that its inclusion in the rod makes it possible to utilize the rod in a refrigerating system in which the usual expansion valve mechanism is completely eliminated. Another major advantage of the present rod including a metering device resides in the fact that by reason of the improved construction a number of these individual rods may be connected in parallel in a single refrigerating system with each rod functioning effectively and independently of the other rod or rods. Another major advantage of the present rod construction lies in the fact that the metering device, in the form of a capillary tube, insures greater efficiency of rod operation by effecting the delivery of the refrigerant in unexpected condition so that the initial expansion of the refrigerant takes place in the rod where it is most effective to absorb heat from the beverage being drawn through the refrigerated rod. Another major advantage of the present rod construction lies in the fact that the metering device, in the form of a capillary tube, provides a simple and effective means for controlling the amount of refrigerant which passes through the individual rod. Another advantage of the present rod construction lies in the fact that the metering device, in the form of a capillary tube, can have its length and the size of its passage so calculated as to insure the delivery of the proper amount of refrigerant to maintain the refrigerant passages of the rod flooded at all times to meet the heat absorbing requirements of the rod.

While the invention has been described in considerable detail with reference to an illustrative embodiment thereof, it is to be understood that various changes may be made in the construction and arrangement of parts in a device embodying the teachings of the present invention without departing from or sacrificing any of the advantages hereinafter claimed.

I claim:

1. A refrigerated tap rod, for dispensing carbonated beverages from a container, said refrigerated rod comprising an intermediate fitting, an upper fitting, a lower fitting, and a plurality of concentrically arranged thin-walled metal

- 5 tubes of high thermal conductivity including a central tube, an intermediate tube, and an outer tube, said central tube extending from said upper fitting to said lower fitting and forming a passage through which the beverage is drawn, said intermediate tube being anchored in said upper fitting concentrically with said central tube and extending downwardly therefrom and cooperating with said central tube to delineate 10 a refrigerant passage surrounding said beverage passage, said outer tube extending from said lower fitting to said intermediate fitting concentrically with said intermediate tube and cooperating therewith to delineate a continuation 15 of refrigerant passage, a refrigerant inlet in said intermediate fitting, a refrigerant outlet in said intermediate fitting, and a metering device interposed between said refrigerant inlet and said refrigerant passage, said metering device 20 serving to control the flow of refrigerant to said refrigerant passage in such quantity as to maintain said passage substantially filled with refrigerant at all times whereby the effectiveness of the refrigerating action of the rod is materially increased.
2. A refrigerated tap rod constructed as set forth in claim 1, in which the metering device is a capillary tube.
3. A refrigerated tap rod constructed as set forth in claim 1, in which the metering device comprises a capillary tube disposed adjacent the outer surface of that portion of the intermediate tube located between said intermediate fitting and said upper fitting.
4. A refrigerated tap rod constructed as set forth in claim 1, in which the metering device comprises a capillary tube of helical form surrounding the portion of said intermediate tube disposed between said intermediate fitting and said upper fitting.
